UNITED STATES PATENT OFFICE.

LOUIS A. REISER, OF WATERBURY, CONNECTICUT, ASSIGNOR OF ONE-HALF TO
G. WEGNER, OF WATERBURY, CONNECTICUT.

BROOM-HOLDER.

1,262,258.

Specification of Letters Patent. Patented Apr. 9, 1918.

Application filed April 16, 1917. Serial No. 162,322.

To all whom it may concern:

Be it known that I, LOUIS A. REISER, a citizen of the United States, residing at Waterbury, in the county of New Haven and State of Connecticut, have invented certain new and useful Improvements in Broom-Holders, of which the following is a specification.

This invention relates to what I shall for convenience term a broom-holder. As I observe the title selected has been adopted primarily for convenience and for the further reason that the article has eminently met the conditions imposed on it in this particular field. Obviously it can be used with equal utility in many other connections; in fact it can sustain any suitable article, and a broom as will be clear is merely one illustration. Among the primary aims I have in view is the provision of a device of the general character indicated which will properly uphold a broom or other implement, but which will permit when desired the easy and ready removal of the article in question or its equivalent. The device can also be inexpensively and easily made.

In the drawings accompanying and forming part of the present specification I have illustrated in detail one of the several convenient forms of embodiment of the invention which to enable those skilled in the art to practice the same will be set forth fully in the following description. As will be evident I do not restrict myself to this exact construction. I may depart therefrom in several respects within the scope of the invention defined by the claim following said description.

Referring to said drawings:

Figure 1 is a top plan view of a holder involving the invention, showing a stick in section between the jaws thereof.

Fig. 2 is a front view of the same, a portion of a broom or equivalent also appearing.

Like characters refer to like parts in both views.

The article can be made from any desirable material, it being preferably, though not essentially, made in one piece from strap metal and being furnished with suitable means whereby it can be fastened to a wall, door or other support to uphold it in posi-

tion to permit its jaws to yieldingly grip the handle of a broom or other part. 55

In the drawings the holder is conveniently made from one piece of strap metal possessing the desired resiliency. It comprises the companion jaws 2 and 3 practically of spiral or at least part circular form. From the rear parts of the jaws there extend backwardly the legs 4 and 5 furnished with outwardly extending feet 6 and 7 which as shown are flat and in the same plane with each other. These feet are perforated as at 8 to receive fastenings such as the screws 9 by which the holder can be held to a wall 10 or other suitable support. The inner ends of the curved jaws 2 and 3 are provided with wings 11 and 12 which as shown converge forwardly and short of or spaced from the inner faces of the front of the curved jaws 2 and 3 respectively. At the back of the holder there is the connecting piece or neck 13, the ends of which are inwardly bowed as at 14 and 15 respectively, the front ends of the inwardly bowed portions being united with the corresponding ends of the parts 11 and 12. The intermediate part of the connecting piece or neck 13 is flat and is 80 adapted to lie against the support 10 so as to strengthen the structure and maintain at all times the jaws 2 and 3 in proper position to receive between them and grip an object which may be the handle 16 of a broom. It 85 will be clear that the radius of the jaws 2 and 3 is in the structure illustrated, greater than that of the broom handle or similar part. 90

It will be supposed that the holder is positioned upon a suitable support and that it is desired to mount a broom or equivalent. In this case the handle is thrust between the jaws 2 and 3 which owing to their resiliency separate laterally until the broom handle is 95 received against the back or connecting neck 13 at which point the jaws will firmly close upon or grip the handle and prevent the broom or like part being accidentally displaced. 100

What I claim is:

A device of the class described comprising a pair of resilient approximately spiral jaws having practically straight shanks provided with outwardly extending attaching feet, a connecting piece approximately in the plane 105

with said feet, between said jaws, and having forwardly and inwardly bowed portions extending into the jaws, and wings connected to the front ends of said bowed portions and extending rearwardly and divergently to each other and united with the free ends of the jaws, the whole being constructed in one piece from strap resilient material, the connecting piece acting as a bearing for the

article gripped between the jaws and being ¹⁰ free of the part to which said attaching feet are connected.

In testimony whereof I affix my signature in the presence of two witnesses.

LOUIS A. REISER.
